CLAIM

I claim the ornamental design for an elongated antenna, as shown and described herein.

DESCRIPTION

FIG. 1 is a perspective view of my elongated antenna;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The broken lines in the drawings illustrate portions of the elongated antenna that form no part of the claimed design.

1 Claim, 5 Drawing Sheets
